CUP OR THE LIKE

Iola G. Marshall, Oakland, Calif.

Application January 14, 1950, Serial No. 7,263

Term of patent 14 years

(Cl. D44—9)

To all whom it may concern:

Be it known that I, Iola G. Marshall, a citizen of the United States, residing at Oakland, State of California, have invented a new, original, and ornamental Design for a Cup or the like, of which the following is a specification, reference being had to the accompanying drawings, forming a part hereof, wherein,

Fig. 1 is a perspective view of a cup showing my new design; and

Figs. 2 and 3 are side elevational views thereof taken at right angles with respect to each other.

I claim:

The ornamental design for a cup or the like, substantially as shown.

IOLA G. MARSHALL.
